(57) **CLAIM**

The ornamental design for a transaction card with stacked account identifier, as shown and described.

DESCRIPTION

FIG. 1 is a rear perspective view of a transaction card with stacked account identifier embodying our design;
FIG. 2 is a rear plan view thereof;
FIG. 3 is a rear perspective view of a second embodiment;
FIG. 4 is a rear plan view thereof;
FIG. 5 is a rear perspective view of a third embodiment;
FIG. 6 is a rear plan view thereof;
FIG. 7 is a rear perspective view of a fourth embodiment;
FIG. 8 is a rear plan view thereof;
FIG. 9 is a rear perspective view of a fifth embodiment;
FIG. 10 is a rear plan view thereof;
FIG. 11 is a rear perspective view of a sixth embodiment;
FIG. 12 is a rear plan view thereof;
FIG. 13 is a rear perspective view of a seventh embodiment;
FIG. 14 is a rear plan view thereof;
FIG. 15 is a rear perspective view of an eighth embodiment;
FIG. 16 is a rear plan view thereof;
FIG. 17 is a rear perspective view of a ninth embodiment;
FIG. 18 is a rear plan view thereof;
FIG. 19 is a rear perspective view of a tenth embodiment;
FIG. 20 is a rear plan view thereof;
FIG. 21 is a rear perspective view of an eleventh embodiment;
FIG. 22 is a rear plan view thereof;
FIG. 23 is a rear perspective view of a twelfth embodiment;
FIG. 24 is a rear plan view thereof;
FIG. 25 is a rear perspective view of a thirteenth embodiment;
FIG. 26 is a rear plan view thereof;
FIG. 27 is a rear perspective view of a fourteenth embodiment;
FIG. 28 is a rear plan view thereof;
FIG. 29 is a rear perspective view of a fifteenth embodiment;
FIG. 30 is a rear plan view thereof;

(Continued)

FIG. 31 is a front perspective view of a sixteenth embodiment;
 FIG. 32 is a front plan view thereof;
 FIG. 33 is a front perspective view of a seventeenth embodiment;
 FIG. 34 is a front plan view thereof;
 FIG. 35 is a front perspective view of an eighteenth embodiment;
 FIG. 36 is a front plan view thereof;
 FIG. 37 is a front perspective view of a nineteenth embodiment;
 FIG. 38 is a front plan view thereof;
 FIG. 39 is a front perspective view of a twentieth embodiment;
 FIG. 40 is a front plan view thereof;
 FIG. 41 is a front perspective view of a twenty-first embodiment;
 FIG. 42 is a front plan view thereof;
 FIG. 43 is a front perspective view of a twenty-second embodiment;
 FIG. 44 is a front plan view thereof;
 FIG. 45 is a front perspective view of a twenty-third embodiment;
 FIG. 46 is a front plan view thereof;
 FIG. 47 is a front perspective view of a twenty-fourth embodiment;
 FIG. 48 is a front plan view thereof;
 FIG. 49 is a front perspective view of a twenty-fifth embodiment;
 FIG. 50 is a front plan view thereof;
 FIG. 51 is a front perspective view of a twenty-sixth embodiment;
 FIG. 52 is a front plan view thereof;
 FIG. 53 is a front perspective view of a twenty-seventh embodiment;
 FIG. 54 is a front plan view thereof;
 FIG. 55 is a front perspective view of a twenty-eighth embodiment;
 FIG. 56 is a front plan view thereof;
 FIG. 57 is a front perspective view of a twenty-ninth embodiment;
 FIG. 58 is a front plan view thereof;
 FIG. 59 is a front perspective view of a thirtieth embodiment;
 FIG. 60 is a front plan view thereof;
 FIG. 61 is a front perspective view of a thirty-first embodiment;
 FIG. 62 is a front plan view thereof;
 FIG. 63 is a front perspective view of a thirty-second embodiment;
 FIG. 64 is a front plan view thereof;
 FIG. 65 is a front perspective view of a thirty-third embodiment;
 FIG. 66 is a front plan view thereof;
 FIG. 67 is a front perspective view of a thirty-fourth embodiment;
 FIG. 68 is a front plan view thereof;
 FIG. 69 is a front perspective view of a thirty-fifth embodiment;
 FIG. 70 is a front plan view thereof;
 FIG. 71 is a front perspective view of a thirty-sixth embodiment;
 FIG. 72 is a front plan view of thereof;
 FIG. 73 is a front perspective view of a thirty-seventh embodiment;

FIG. 74 is a front plan view thereof;
 FIG. 75 is a front perspective view of a thirty-eighth embodiment;
 FIG. 76 is a front plan view thereof;
 FIG. 77 is a front perspective view of a thirty-ninth embodiment;
 FIG. 78 is a front plan view thereof;
 FIG. 79 is a front perspective view of a fortieth embodiment;
 FIG. 80 is a front plan view thereof;
 FIG. 81 is a front perspective view of a forty-first embodiment;
 FIG. 82 is a front plan view thereof;
 FIG. 83 is a front perspective view of a forty-second embodiment; and,
 FIG. 84 is a front plan view of thereof.
 The broken lines are directed to environment and form no part of the claimed design. The rectangular boxes represent positions of alphanumeric or symbolic characters of an account identifier.
